BY *Julian Holschup*
ATTORNEY.

UNITED STATES PATENT OFFICE

CARMINE PIETRACATELLA, OF NEW YORK, N. Y.

TROUSER SEAM PRESSING MACHINE

Application filed December 23, 1929. Serial No. 415,989.

This invention relates to new and useful improvements in a trouser seam pressing machine.

The invention has for an object the provision of a device of the class mentioned which is of simple durable construction, dependable in use and efficient in action, and which can be manufactured and sold at a reasonable cost.

10 The invention proposes a counterbalance lever with a heated presser driver roller engaging with a presser idler roller upon operation of a means for closing the said lever, which is pivotally mounted upon a vertical portion of a base. A seam spreader and cloth dampener is also mounted to the front of the said driver roller. The invention further proposes a means for alternately turning the driver roller in opposite directions 15 for pressing the seam in several stages and moving the roller forward more than backward so that the seam is moved forward.

For further comprehension of the invention, and of the objects and advantages thereof, reference will be had to the following description and accompanying drawings, and to the appended claims in which the various novel features of the invention are more particularly set forth.

20 In the accompanying drawings forming a material part of this disclosure:—

Fig. 1 is a side elevational view of a device constructed according to this invention.

Fig. 2 is an end elevational view looking 25 from the right hand side of Fig. 1.

Fig. 3 is a fragmentary enlarged vertical sectional view taken on the line 3—3 of Fig. 1.

Fig. 4 is a fragmentary side elevational 30 view similar to a portion of Fig. 1, but disclosing the modification.

Fig. 5 is a plan view of Fig. 4.

Fig. 6 is a fragmentary sectional view 35 taken on the line 6—6 of Fig. 5 and showing the wheel only.

The trouser seam pressing machine consists of a bracket having a base portion 10 connected with a vertical portion 11 formed with a lateral projecting portion 12, a presser idler roller 13 mounted on and near the

free end of said projecting portion 12, a counterbalanced lever 14 pivotally mounted on said vertical portion 11, a heated presser driver roller 15 mounted on said lever 14 in line with the idler roller 13, means for rotating the driver roller 15, means for moving said lever to bring said rollers into pressing engagement 14 so that the rollers engage each other, and a seam spreader 16 and cloth dampener 17 mounted on said lever 14 to the front 55 of said driver roller.

The bracket 10 is formed with a flat bottom 18 for resting upon a table or bench, and being attached thereon. The projecting portion 12 is formed with a recess 19 in which the idler roller 13 engages so that it slightly protrudes from the top. A transverse pin 20 is mounted across the recess and the roller is supported upon this pin by ball bearings 21. The lever 14 is pivoted intermediately at 22 and its rear end supports a rod 23 provided with a slidable weight 24 constituting partial counterbalancing of the lever. The counterbalancing is concluded with a motor 25 mounted upon the lever 14 to the 60 rear of the pivot 22.

The lever 14 is formed with a downward turned front end 26 carrying pillar blocks 27 supporting the said driver roller 15. This roller is of hollow construction as shown 65 in Fig. 3, and a coaxial gas pipe 28 extends into the hollow. This gas pipe is provided with burner openings 29 ignitable thru a passage 30 formed in the roller. The roller 15 is also heated by an exterior burner 31 70 connected with a flexible gas pipe 32. The means for rotating the driver roller 15 consists of an extended shaft 33 from the roller 75 and connected with a pulley 34 engaged by a belt 35 also engaging the pulley of the motor 25.

The means for closing the lever 14 consists of a radial arm 36 having one end connected coaxially on the lever 14 and a connecting link 37 extended downwards and connected with any conventional foot pedal not shown on the drawing. The seam spreader 16 has a pointed horizontal portion 38 adapted to engage in the seam and spread the two edges open. A screw 39 supports the seam 80

spreader upon the downturned lever 26. The dampener 17 consists of a container 40 for holding water or any other suitable liquid and having a reduced bottom drip nozzle 41. This container is supported by a bracket 42 upon the down turned portion 26 of the lever.

In the modified form of the device illustrated in Figs. 4, 5 and 6, a means has been shown for alternately turning the driver roller 15 in opposite directions for pressing the seam in several stages and moving the roller forward more than backwards so that the seam is moved forwards. This means consists of a shaft 43 supporting the driver roller 15 and formed at one end with a knurled portion 44. A large drum 45 loosely engages the knurled portion 44 and carries coupling jaws 46 slidably arranged so that in depressed conditions rotations from the drum 45 are communicated to the shaft 43. A spring 47 is secured upon the drum 45 and engages the jaw 46 so as to normally urge it into a slightly extended position constituting the disengaged condition of the jaw.

A band 48 encircles the drum 45 and is adapted for depressing the jaws 46 into their operative conditions. This is accomplished by a spring 49 acting between the ends 50 of the band for normally contracting it. A rod 51 is slidably mounted upon the lever 14 and passes thru one of the ends 50 and engages against the other of the ends so that upon forward motion, it may spread the ends for slightly opening the band. The end 50 thru which the rod 51 slidably passes is fixed as at 52 upon the lever 14. A spring 53 acts between the rod 51 and the lever 14 for normally urging the rod rearwards against a small wheel 54 fixed upon a shaft 55 carrying a pulley 34 engaged by the said belt 35. The small wheel 54 is provided with a projecting cam portion 56 extending about one quarter of its periphery. A pin 57 eccentrically projects from the small wheel 54 and supports one end of a connecting rod 58 whose other end is supported upon a pin 59 eccentrically mounted upon the large drum 45.

Rotations from the pulley 34 are transmitted to the small wheel 54. Motion of wheel 54 causes the connecting rod 58 to reciprocate and rock the drum 45 forwards and rearwards. This rocking motion is transmitted to the presser roller 15. Each time the cam portion 56 passes the end of the rod 51, the rod is moved forward for expanding the band 48 so that the springs 47 may move the jaws 46 slightly outwards and permit the drum 45 to idle during part of its oscillations. Obviously, for each rotation of the wheel 54, the drum 45 goes forward and backwards but in the backward movement only part of the motion is transmitted to the

presser roller 15 which causes the seam being pressed to advance.

In operation of the device, a trouser leg, as schematically indicated by dot and dash lines 62, is engaged upon the lateral projection 12 so that the seam 63 engages upon the idler roller 13. Then the pedal is depressed for moving said lever to bring said rollers into pressing engagement, so that the driver roller 15 engages the seam. The spreader 16 opens the seam and the material being pressed is dampened by drops from the container 40. When the seam is completely pressed, the pedal is released so that the lever 14 opens. Next the trouser leg is turned thru an angle of 180 degrees so that the other seam 64 may be similarly pressed.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A trouser seam presser machine, comprising a bracket having a base portion connected with a vertical portion formed with a lateral projecting portion, a presser idler roller mounted on and near the free end of said projecting portion, a counterbalanced lever pivotally mounted on said vertical portion, a heated presser driver roller mounted on said lever in vertical alignment with said idler roller, means for rotating the driver roller, means for moving said lever to bring said rollers into pressing engagement, and means for alternately turning the driver roller in opposite directions for pressing the seam in several stages and moving the roller forward more than backward so that the seam is moved forwards.

2. A trouser seam presser machine, comprising a bracket having a base portion connected with a vertical portion formed with a lateral projecting portion, a presser idler roller mounted on and near the free end of said projecting portion, a counterbalanced lever pivotally mounted on said vertical portion, a heated presser driver roller mounted on said lever in vertical alignment with said idler roller, means for rotating the driver roller, means for moving said lever to bring said rollers into pressing engagement, and means for alternately turning the driver roller in opposite directions for pressing the seam in several stages and moving the roller forward more than backward so that the seam is moved forwards, said means including a drum loosely mounted on a shaft connected with said driver roller, and means for coupling said drum to said shaft during oscillation of the drum and disconnecting the

coupling during part of backward movement
of said oscillation.

3. A trouser seam presser machine, comprising a bracket having a base portion connected with a vertical portion formed with a lateral projecting portion, a presser idler roller mounted on and near the free end of said projecting portion, a counterbalanced lever pivotally mounted intermediate of its ends on said vertical portion, a heated presser driver roller journaled on the forward end of said lever in vertical alignment with said idler roller, means including a motor for rotating the drive roller, means for moving said lever to bring said rollers into pressing engagement, and said motor mounted on the rear end and behind the pivot point of the said lever so that said motor partially counterbalances said jaw.

20 In testimony whereof I have affixed my signature.

CARMINE PIETRACATELLA.
